LIQUID FLOW REGULATOR .

Harry C. Fischer, Plymouth, Mich., assignor to
Temprite Products Corporation, Detroit, Mich.,
a corporation of Michigan

Application October 9, 1947, Serial No. 778,877

4 Claims. (Cl. 137—505)

1

The invention relates to apparatus for automatically regulating the flow of liquids so as to provide a uniform rate of flow notwithstanding variation of the pressure at which the fluid is supplied to the apparatus.

The main object of the invention is to provide an automatic flow regulator which is capable of affecting uniform flow under large variation of the supply pressure and yet is small, compact, of simple construction and susceptible, correspondingly, of production at low cost.

A further object of the invention is to provide a flow regulator having parts that lend themselves to low cost methods of production.

Other objects of the invention, more or less incidental or ancillary to those above stated will be apparent from the description which follows.

With the indicated objects in view, the invention consists in certain combinations and arrangements of parts which will be pointed out and explained in connection with the accompanying drawing showing a preferred embodiment and, finally more particularly defined in the appended claims.

In the drawing,

Fig. 1 is a side elevation of a combined flow regulating and valve device embodying the invention.

Fig. 2 is a horizontal section on the line 2—2 of Fig. 1.

Fig. 3 is a vertical section on the broken line 3—3 of Fig. 1.

Fig. 4 is a section on the line 4—4 of Fig. 3.

Referring in detail to the construction illustrated, 1 designates generally an integral casing element having a vertically disposed inlet section 2, a horizontally extending discharge section 3 with outlet opening 3a and a diaphragm-housing section 4.

The inlet section 2 of the casing member 1 is internally threaded to receive a fitting 5 to which in turn is secured, as by brazing, a male coupling member 6 which provides an inlet 6a for the casing structure. A female coupling member 7 has a swiveling engagement with the member 6.

A valve member 8 and a cooperating soft seat 9 of rubber or the like are provided to control the fluid passage of the casing. Valve 8 may conveniently be formed as shown from hexagonal bar stock so that it will be guided for axial movement in the bore of member 5. The valve is normally pressed against the seat 9 by a coiled spring 10 resting upon the internal flange of member 6. Means for opening the valve 8 is provided in

2

the form of a plunger 11 which has its enlarged upper end slidably fitted in the bore 1a of the casing 1, while its lower end of reduced diameter engages the socket formed in valve 8. The enlarged upper end of spindle 11 is grooved to receive an O-ring packing 12.

The casing element 1 is formed with a horizontal bore 1b which has its axis coincident with that of the outlet branch 3 of the casing and laterally offset from the axis of the inlet bore 1a of the casing so that the adjacent sides of the two bores 1a and 1b intersect as shown in Fig. 3 to provide a communicating control aperture 1c between them which divides the passageway 15 through the casing structure into inlet and outlet parts. In the bore 1b is mounted a plunger generally designated by the numeral 13 and comprising a piston 13a and a stem 13b. The piston 13a slidably fits the bore 1b and cooperates with the aperture 1c as shown in Fig. 2 to control the flow from the bore 1a into the bore 1b. The stem 13b, extending through bore 1b, forms an annular space 1d of which stem 13b constitutes the inner wall. The end of stem 13b extends through the center of a flexible diaphragm of rubber or the like and is fastened thereto with a fluid-tight joint by nut 15 and washers 16, 17. The periphery of the diaphragm 14 is secured with a fluid-tight joint to the section 4 of the casing by means of sleeve 18 which is exteriorly threaded 20 to engage mating threads in casing part 4, a metal ring or washer 19 being interposed between the diaphragm and the sleeve 18. Thus a diaphragm chamber 4a is provided with an annular opening 1d adjacent the control aperture 1c.

The regulating plunger 13 is drilled out at its free end to form an axial bore 13c which at one end communicates directly with the bore 1b and at its other end communicates with said bore 40 through radial apertures 13d and 13e at points adjacent the piston 13a of the plunger. This bore 13c is made sufficiently small to insure maintenance of the necessary regulating pressure in the diaphragm chamber.

It will be noted that a portion of the annular space 1d, the radial apertures 13d, 13e and axial bore 13c constitute conduit means with several turns, or changes of direction, for conveying liquid from the control aperture 1c into the outlet part of the passage-way of the casing 1. It is also apparent from Fig. 2 that liquid projected through the control aperture, moving at an acute angle to the plunger stem 13b, strikes the side of the stem within the annular opening 1d of the diaphragm chamber 4a. Thence the flowing liquid

stream continues through radial apertures 13d, 13e and bore 13c into the discharge part of the casing. Thus the liquid on the outlet side of control aperture 1c has free access through opening 1d to the diaphragm chamber 4a and the inner side of the diaphragm is subjected to whatever pressure is set up in the annular space or opening 1d. On its other side, the diaphragm is subject to the pressure of a coil spring 20 which is interposed between the diaphragm and a threaded disk 21 which adjustably engages internal threads in the sleeve 18. By adjustment of disk 21, which is slotted to receive an adjusting tool, the position of the spring 20 in its unloaded state, can be varied to determine the position of diaphragm 14 and piston 13. In assembling the device, the disk 21 preferably is adjusted so that the spring 20 in a substantially unloaded state will position the right end of the piston 13a (as viewed in Fig. 2) slightly to the right of a plane through the axis of the inlet bore 1a and at right angles to the discharge bore 1b.

For explanation of the operation of the device, it will be assumed that the inlet opening 6a of the casing structure is connected with some suitable source of fluid supply by means of coupling 7 and that the discharge branch of the casing is connected with conduit means leading to a point of discharge or of use of the fluid under pressure. The device is applicable to a wide variety of uses or applications but in the specific form illustrated is designed to control the supply of water to a drinking fountain and, as water supply pressures are likely to vary widely, a description of the operation of the device in such an application will serve to explain its advantageous operating characteristics.

In the operation of drinking fountains, the flow of water is normally shut off and is turned on by the user of the fountain by the operation of a control valve by some manual device which, in this case, will be assumed to engage the plunger 11 and depress it against the tension of spring 10 to open the control valve 8. Before the valve 8 is opened water filling the apparatus on the outlet side of the valve is at the pressure of the atmosphere. On the opening of the valve water under pressure passes from the bore 1a through aperture 1c into the annular space 1d and thence through apertures 13d, 13e and bore 13c to the passage-way in discharge branch 3 of the casing. As the water encounters the resistance of the restricted bore 13c pressure builds up in the diaphragm chamber and causes the diaphragm to position the piston 13a, according to the supply pressure, in a manner to regulate flow through the aperture 1c and tending to maintain the rate of flow therethrough constant. Thus if the supply pressure in bore 1a increases, the pressure on the diaphragm will increase and the diaphragm and piston will move, against the pressure of spring 20, to reduce the aperture 1c and throttle the flow so that the pressure in the discharge passage of the casing and the rate of flow therethrough will tend to remain constant notwithstanding variations in the fluid supply pressure.

This result is secured also by prior small liquid flow regulators of the spring-pressed diaphragm type but only within a quite limited range of supply pressure variation. Beyond such limited variations the small diameter diaphragm of the prior device fails to make the required compensation for the increase in supply pressure because

of the internal tensional forces set up in the diaphragm between the central and peripheral parts thereof as it departs from flat to conical or frusto-conical form, these internal forces, which increase rapidly with the diaphragm movement, being added to the substantially constant resistance of the diaphragm spring. The resulting variations in the resistance to the diaphragm movement could be avoided by increasing the diameter of the diaphragm to give it sufficient capacity for free axial movement, but such change would unduly increase the size, weight and cost of the device and so does not offer a practical solution of the problem.

By the present invention the problem in question is solved by conducting the flow of the liquid from the inlet bore 1a into the outlet part of the casing in the manner already indicated which is such that a velocity effect of the liquid forced through the control aperture 1c by the high inlet pressure is applied to the liquid in annular opening 1d and chamber 4a and such that this velocity effect increases with increase in the liquid supply pressure.

The manner in which this is accomplished in the construction illustrated will be understood from a consideration of Fig. 2. Here it will be seen that the center of the liquid stream, or, in other words, the direction of the liquid flow, is in a line through the axis of the inlet bore 1a and the center of the effective part of aperture 1c; and also that the flow will always be at an acute angle against the plunger stem 13b and directed toward the diaphragm 14. Consequently the liquid stream will always have a velocity effect at least part of which will be converted into liquid pressure in the annular space 1d and the communicating chamber 4a. This velocity-generated pressure is added to and increases the static pressure in the diaphragm chamber but none of the velocity effect generated at the control aperture is present in the liquid stream delivered into the outlet part of the casing passage-way because such velocity effect (or momentum) is a directional or vector quantity and any part of it not converted into static pressure in the diaphragm chamber is dissipated in the flowing liquid by the latter's changes of direction, exceeding 90 degrees, in passing from the annular space 1d to the bore 13c.

It follows that the diaphragm pressure which opposes the coil spring 20 will always include the velocity effect element explained. Furthermore, it will be seen that as the supply pressure in the inlet bore increases, the rightward movement of the plunger due to the increased static pressure against the diaphragm will make the angle of liquid flow into the annular part of the bore 1b more acute to the side of stem 13b, so that the direction of the flow past the plunger and generally toward the diaphragm gradually approaches a line normal to the diaphragm and the velocity-effect component of the pressure on the diaphragm is the resultant of both the increase of the supply pressure and the change in direction of the flow past the plunger, both factors acting to increase the effect. The result is that the variable velocity effect, increasing with the increase of fluid supply pressure, compensates for the increasing internal stress in the small diameter diaphragm so that the latter serves adequately to compensate for inlet water pressure variation over a wide range of values.

In the specific construction shown in Fig. 2, liquid flowing in bore 13c of stem 13b has a

velocity effect that generates pressure in the discharge section 3 with an equal and opposite reaction on stem 13b toward the diaphragm 14, which reaction is added to the outward fluid pressure on the diaphragm. However, this velocity effect does not vary as does that in the annular passage 1d and diaphragm chamber 4a because it is always in the same direction and is generated by the substantially constant pressure in passages 13d, 13e. As already noted, these latter passages are not subject to the variable velocity effect in passage 1d. Consequently the pressure in them is determined by the over-all or compensated regulating effect of the diaphragm.

Thus, as a result of the present improved construction, a small, light-weight and low-cost regulating device is produced capable of maintaining an adequately uniform discharge of water over a range of inlet pressure variation eight or ten times as great as is permissible without the automatically varied velocity pressure effect. The practical significance of this for drinking fountain application is that one setting or adjustment of the device at the factory will adapt a drinking fountain to operate with a substantially uniform discharge stream for any supply pressure likely to be encountered, whereas it has been necessary with prior fountain equipment to adjust the regulator in the field to different average supply pressures at different points of use and, even then, if the supply pressure varies widely an objectionably variable discharge stream is secured.

Where both the automatic regulation and the manual control of flow are required simplicity and low cost are attained by combining both functions in the one fitting. However, it is apparent that the manual shutoff valve can be omitted when only the regulating function is required.

It will be appreciated that since the plunger 13 functions only as a regulator its piston need not have a highly accurate fit in the bore of the casing, also that the formation of passages in the plunger permits corresponding simplification of the casing structure while the passages are readily formed in the small symmetrical plunger part by low cost machining operations.

It will be apparent, too, that the automatically varied velocity effect upon which the invention is based can be secured with various forms of casing and regulating plunger constructions equivalent mechanically to the construction shown and described and it is to be understood that the invention includes such modified constructions as are properly within the bounds of the appended claims.

What is claimed is:

1. In liquid flow control apparatus, the combination of a casing structure having an inlet opening and an outlet opening and a connecting passage-way between the said openings including a control aperture and having walls arranged to form in cooperation with a diaphragm a chamber having an opening adjacent to the outlet side of the control aperture in a position to receive liquid projected through said aperture and against a wall of the opening; movable means associated with the casing structure for controlling the liquid flow through the casing passage-way to maintain uniform the rate of said flow

under varying liquid supply pressure, said movable control means comprising a plunger interposed in the passageway on the outlet side of and adjacent to the control aperture to variably restrict flow there-through, a diaphragm having its central part connected to the plunger and its peripheral part connected to the diaphragm chamber walls, said diaphragm, in response to liquid pressure on the inner side thereof, serving to move the plunger in the direction to reduce the capacity of the control aperture and meanwhile sustaining internal distortional stresses opposing the movement which increase as the movement progresses, and a coil spring engaging the outer side of the diaphragm to resist the specified movement of the diaphragm and plunger; and conduit means for conveying liquid from the control aperture to the discharge part of the casing passage-way in a path that changes direction not less than 90 degrees, the control aperture, the inlet part of the casing passageway adjacent said aperture, the plunger and the said wall of the diaphragm chamber opening being formed and arranged to project a liquid stream through the aperture and against said wall at an acute angle and to decrease the angle of incidence of the stream on the said wall as the plunger moves in the aperture-closing direction.

15 2. A liquid flow control apparatus as claimed in claim 1 in which the plunger is formed with passages to convey the liquid from the control aperture to the outlet part of the casing passageway.

20 3. Liquid flow control apparatus as claimed in claim 2 in which the plunger comprises piston and stem parts and the plunger passages comprise a radial passage in the stem adjacent to the end of the piston and an axial passage through the piston which receives fluid from the radial passage and delivers it into the outlet part of the casing passageway.

25 4. Liquid flow control apparatus as claimed in claim 1 in which the casing passageway has a straight inlet part and a straight outlet part disposed in different directions and spaced apart laterally with a port between them to form the control aperture, and in which the plunger is movably arranged in the outlet part of the passageway and comprises a piston part which serves by its movement to vary the size of the said aperture and a stem part which is connected to the diaphragm.
